UNITED STATES PATENT OFFICE.

CLAUDE H. ABBOTT, OF LISBON, NORTH DAKOTA.

DRAFT REGULATOR.

Application filed January 24, 1921. Serial No. 439,581.

To all whom it may concern:

Be it known that I, CLAUDE H. ABBOTT, a citizen of the United States, residing at Lisbon, in the county of Ransom and State 5 of North Dakota, have invented certain new and useful Improvements in Draft Regulators; and I do declare the following to be a full, clear, and exact description of the invention, such as will enable others skilled 10 in the art to which it appertains to make and use the same.

This invention relates to an improved draft regulator, that is, a device which is designed to automatically control the draft 15 devices of a hot-water or steam heating system according to the intensity of the fire in the fire-box, one of said draft devices being open when the other one is closed. Thus, when the fire is low, the check damper in 20 the smoke stack is closed and the front draft door is open and as soon as the heat reaches a predetermined temperature, just the reverse is true, that is, the check damper is opened and the front draft door is closed. 25 In this way, a uniform degree of heat is obtained at all times.

The principal object of the invention is to provide a draft regulator which is associated with and actuated by the circulating 30 pipe leading from the boiler to the radiators in the various rooms, the device including a lever and a heat-controlled actuator bar or means therefor which is operated by the lengthening or shortening of 35 said circulating pipe under the influence of the heated fluid passing therethrough.

Another object of the invention is to provide a device of this class including a chain 40 adjusting device which makes it possible to regulate the amount of opening of the draft devices and also makes it possible to render either of such devices entirely inoperative, by slackening the chain.

A further object of the invention is to 45 provide a device of this class which is very simple in construction, easy to install, positive in operation, and extremely inexpensive to both the manufacturer and the user.

Other objects and advantages of the invention will be apparent during the course 50 of the following description.

In the accompanying drawings forming 55 a part of this specification and in which like numerals are employed to designate like parts throughout the same:

Figure 1 is an elevational view of a por-

tion of a conventional type of hot-water heating system equipped with a draft regulator, constructed in accordance with this 60 invention.

Figure 2 is an enlarged side elevational view of a portion of the regulator showing more clearly the manner in which the lever is connected with the circulating pipes.

Figure 3 is a top plan view of so much of 65 the structure as shown in Fig. 2, showing more clearly the chain adjusting device.

For the purpose of illustration and to enable the reader to obtain a clear understanding of the device, I have shown in the 70 drawings, a portion of the conventional type of hot-water heating system. Referring to Fig. 1 wherein this showing appears, the letter B designates a conventional type of boiler equipped with a front draft door 75 C, and a smoke stack S, in which is a check damper D. The system, as is usual, also includes a fluid circulating pipe P which leads from the boiler to the radiators in the various rooms. The construction and ar- 80 rangement herein shown and described can be varied as the draft regulator is applicable to various types of similar heating systems. The detail description so far as it has gone, sets forth parts which do not 85 form any part of this invention. The invention resides in the construction and arrangement of the draft regulator.

The draft regulator above referred to comprises, in its preferred form, a relatively 90 long lever 1 fulcrumed on the circulating pipe P, a relatively long heat controlled operating bar 2, connections 3 between the lever 1 and draft devices, and a chain adjusting device 4 carried by the aforesaid lever 1. 95 More specifically described, it is to be stated that the lever 1 is in the form of a flat metal bar having an enlarged head 5 at one end provided with a notch 6 for reception of the shank of a headed stud or pivot pin 7 on 100 the collar 8 which is fitted on the circulating pipe P. At this point, I wish to direct attention to the fact that the collars 8 and 8^a will be employed only when the device is being placed on a circulating pipe which is 105 being installed, and if the pipe is already in position, suitable means (not shown) will be substituted for these collars. The bar 2 is of considerable length and is preferably composed of wood, which material is not so 110 liable to become expanded by the heated fluid passing through the circulating pipe.

- on which it is arranged. One end of this arm is pivotally connected to the head 5 of the lever as indicated at 9 and the opposite end thereof is rigidly or pivotally connected to another collar or clamp 8^a on the circulating pipe at a distance spaced from the first named collar. Set-screws 10 and 10^a are preferably used in connection with the collars in order to prevent possible slippage.
- 5 10 With this construction and arrangement, it will be seen that the heated fluid passing continuously through the circulating pipe will cause the latter to shorten or lengthen due to the contraction and expansion thereof.
- 15 20 When it becomes so expanded or contracted, the collars are moved toward or from each other as the case may be and the pull of the actuating bar 2 on the pivoted end of the lever 1 causes the latter to rock about its pivot and open or close the dampers according to the direction in which it moves, chains 3, as before stated, serving as connections between the dampers and lever 1. At this point, it is thought well
- 25 30 to state that the damper D or the lever will be equipped with a counter-weight to normally retain the damper D closed and to retain the lever in the horizontal position disclosed in Fig. 1. When the parts are in this position, it is obvious that one of the chains is sufficiently taut to raise the draft door C.
- As before intimated, the device also includes a chain adjusting device 4 and this device in its preferred form comprises a drum 11 rotatably mounted on a laterally extending pin 12 carried by the lever 1, said pin being disposed near the free end of said lever. It is to be noted that under normal conditions, the drum does not rotate but is substantially rigid, being held in such a position by means of a coiled spring 13 which forces it against a stop 14 on the end of said pin. The ends of the chain are wrapped around this drum and should it be desired to render either of the dampers inoperative, this may be done by manually rotating the drum in such a way as to slacken the operating chain for that particular damper. Attention is again directed
- 35 40 45 50 55 60 to the fact that the drum does not rotate except when so moved by hand. If desired, one of the heads of the drum may be equipped with a pointer or indicator 15 for co-operation with a dial or scale 16 also carried by the aforesaid lever. Thus, a gage is provided which may be effectively employed to regulate the amount of opening of the dampers or to determine just how much to slacken the chains in order to render the dampers inoperative.
- Briefly described, the operation of the device is as follows: The variation in temperature of the hot water or steam passing through the circulating pipe P causes the latter to expand or contract as the tempera-
- ture rises or falls. Such expansion of the pipe causes it to lengthen slightly as is well known. In so doing, the collars or clamps are moved away from each other and a lengthwise movement is imparted to the bar 2, causing it to exert a pull on the head 5 of the lever 1 and in turn rock this lever around its pivot 7. The lever then assumes a slightly upwardly inclined position and as it moves to such a position, it draws the chain 3 upwardly and opens the check damper D in the smoke stack. The lever by taking this position permits the chain 3^a to slacken sufficiently to permit the front draft door C to close by gravity. When the pipe P contracts and assumes its normal position, the parts are returned to the position disclosed in Fig. 1. If the weight of the lever, drum and other parts which it carries, and weighted arm of the check damper D is insufficient to overbalance the front draft door C, an additional weight may be connected to the lever to insure proper opening of the draft door. Should it be desired to slacken or adjust the chains for any of the reasons heretofore referred to, this may be accomplished by manually rotating the drum 11 as before stated, the indicating device or gage functioning to enable the operator to determine just how much to slacken or tighten the chains as the case may be.
- A careful consideration of the foregoing description taken in connection with the drawings, is thought to be sufficient to enable persons skilled in the art to which the invention relates to obtain a clear understanding of the same. Therefore, a more lengthy description is deemed unnecessary.
- Since probably the best results may be obtained with the construction and arrangement herein shown and described, this construction and arrangement is elected as a preferred embodiment of the invention. However, I wish it to be understood that various minor changes within the scope of the claims may be resorted to.
- I claim:
1. The combination with a hot water or steam heating system embodying a boiler, a draft device, and a circulating pipe, of a lever pivotally mounted on the latter and actuated when it is contracted or expanded, said lever being provided at its free end with a laterally extending axle, a drum rotatable on said axle, the latter being provided at its free end with a stop, and a coiled spring arranged between said drum and lever and surrounding said axle for normally preventing rotation of said drum but permitting it to be rotated by hand, and a chain having one of its ends connected with said draft device and its other end wound around said drum.
  2. In a draft regulator, a lever provided

at its free end with a lateral extension providing an axle, a drum rotatable on said axle, a stop on the free end of the latter, a coil spring surrounding the axle and interposed between the drum and the lever to normally prevent rotation of the drum but permitting it to be manually rotated by hand, valve-operating chains wound on said drum, and heat-controlled means connected with the pivoted end of said lever for swinging it about its pivot.

3. In a draft regulator for furnaces and the like, a lever having a head at one end formed with a notch, an actuating bar pivotally connected at one end with said head, a pin extending laterally from the free end of said lever, a stop on the free end of said pin, a drum rotatable on said pin and bearing against said stop, flexible valve operating elements wound in opposite directions on said drum, and a coil spring surrounding said last named pin, being interposed between the drum and the lever and serving to hold the drum against rotation normally, permitting it to be turned by hand.

4. A draft regulator comprising a pair of collars adapted to surround the hot fluid circulating pipe or the like, said collars being spaced apart but being movable toward and

from each other to enable them to be adjusted, set screws carried by the collars and engaging the aforesaid pipe to retain the collars in various adjusted positions, a headed stud carried by and projecting from one collar, a lever having its inner end enlarged to form a head, said head being formed with a notch removably receiving the shank of the aforesaid stud, an actuating bar for the lever having pivotal connection at one end with the head of the lever at a point above the stud and being secured at its opposite end to the other collar, and valve operating means associated with the free end of the lever.

5. In a draft regulator, a lever provided at its free end with a lateral extension providing an axle, a drum rotatable on the axle, a stop on the free end of the axle, a dial surrounding the inner end of the axle, a pointer carried by the drum and co-operable with the graduations on the dial, and a coiled spring surrounding the axle between the drum and the dial to hold the drum in various set positions.

In testimony whereof I have hereunto set my hand.

CLAUDE H. ABBOTT.
